UNITED STATES PATENT OFFICE

AUGUST H. NORDHAUSEN, OF NEW YORK, N. Y.

DESIGN FOR A MANIKIN HEAD OR SIMILAR ARTICLE

Application filed April 21, 1930. Serial No. 35,334. Term of patent 3½ years.

To all whom it may concern:

Be it known that AUGUST H. NORDHAUSEN, a citizen of the United States, and resident of New York city, in the county of New York and State of New York, has invented a new, original, and ornamental Design for a Manikin Head or Similar Article, of which the following is a specification, reference being had to the accompanying drawing, forming part thereof, in which—

Fig. I is a perspective view of a manikin head showing my new design.

Figs. II, III, and IV are top plan, side elevational, and front elevational views, respectively, of said manikin head.

I claim:

The ornamental design for a manikin head or similar article, as shown.

Dated, New York city, April 19th, 1930.

AUGUST H. NORDHAUSEN.
